ILLUMINATION CONTROL SYSTEM

Frank R. Elder, Schenectady, and Harold B. La Roque, Scotia, N. Y., assignors to General Electric Company, a corporation of New York

Application July 9, 1932, Serial No. 621,620

12 Claims. (Cl. 176—124)

This invention relates to illumination control systems, more particularly to systems for controlling the intensity of illumination of luminous discharge devices, such for example as commercial 5 neon tubes, and it has for an object the provision of a simple, reliable, inexpensive and efficient system of this character.

Luminous discharge devices of this type require a high breakdown voltage in order to initiate the discharge and for this purpose they are usually supplied with an alternating voltage through a step-up transformer. Due to the high break-down voltage required and to the interruption of the discharge each time the alternating 10 voltage passes through zero, the problem of dimming tubes of this character is especially difficult. The dimming range with the known methods of resistance dimming is limited to a very small portion of the visible range of the tube, beyond 15 which either a perceptible and intolerable flicker occurs or the tube is entirely darkened. Accordingly a further object of this invention is the provision of means for extending the dimming range of the tube, and more specifically to dim the tubes 20 smoothly and gradually through substantially the full range of visibility from maximum brilliance to complete darkness without perceptible flicker.

In carrying the invention into effect in one form 25 thereof a luminous discharge tube is supplied with an alternating voltage, and means are provided for controlling and varying the point in the cycle of said voltage at which the discharge is initiated throughout substantially the entire portion 30 of each half cycle of the applied voltage, thereby varying the intensity of illumination of the tube, gradually and smoothly from maximum brilliance to complete darkness. In a specific form of the invention, means preferably in the form of an 35 impedance device are provided for preventing the tube voltage from attaining the break-down value during a predetermined portion of the cycle of the alternating voltage, and additional means, preferably suitable electric valve apparatus, are provided for rendering the device ineffective and 40 initiating the discharge at desired points in the tube voltage cycle and thereby controlling the intensity of illumination of the tube as desired.

For a better and more complete understanding 45 of the invention, reference should now be had to the following specification and to the accompanying drawing in which Fig. 1 is a simple diagrammatical representation of an embodiment of the invention and Fig. 2 is a chart of curves 50 illustrating certain tube operating characteristics

and facilitating an understanding of the invention.

Referring now to the drawing, a cold cathode type gas-filled luminous discharge device 10, such for example as the well-known neon tube, is supplied with alternating voltage from a suitable source such for example as that represented by the three supply lines 11 by means of a suitable step-up transformer 12 to the terminals of the secondary winding of which the cathodes 10a and 10b are directly connected and the primary winding of which is connected to the middle and lower supply lines of the source 11 by means of conductors 13, 14, 15 and 16.

The neon tube usually comprises an elongated 15 envelope having an electrode, preferably of the cold cathode type, at each extremity thereof and is filled with neon gas. In order to initiate the discharge in a luminous tube of this character, a 20 high initial voltage is necessary to ionize the included gas and overcome the drop at the electrode in each end of the tube. This ionization begins at the electrodes and practically instantaneously extends throughout the entire length of the tube, causing the gas to glow with its characteristic 25 color.

On account of the negative resistance characteristics of luminous discharge tubes, current 30 flowing in the tube must be limited in order to prevent damage of the tube.

The relationship between the voltage existing 35 at the terminals of the tube and the discharge current flowing in the tube is clearly shown by curve 17 in Fig. 2 in which positive ordinates represent tube voltage and abscissæ represent 40 discharge current. A very high initial voltage represented by the peak 17a is required to break down the tube and initiate the discharge. Thereafter, the voltage drops rapidly to a point 17b at 45 which the current is sufficient to render the discharge visible. From this point the current increases to a point 17c and it will be observed that this increase in current is accompanied by a decrease in voltage across the tube which is referred to as the negative resistance characteristic 50 of the tube. The range between the points 17b and 17c is the useful glow range of the tube. If the current exceeds the value represented by the point 17c damage results to the tube. The current 55 therefore, must be limited to a value between the points 17b and 17c and this current limitation is obtained by designing the transformer 12 to have a high inherent reactance and a relatively high exciting current. The high reactance current limiting characteristics of the transformer

12 is illustrated by curve 18 in Fig. 2 of the drawing in which it will be observed that the terminal voltage of the transformer decreases rapidly with increasing current to a point 17a at which the 5 curve 18 crosses the curve 17. Thus, the discharge current of the tube is stabilized at a value represented by the point 17a. Furthermore, due to this design of the transformer, the voltage applied to the tube is steeply peaked so that the 10 instantaneous values thereof are equal to or greater than the starting voltage of the tube through substantially the entire portion of each half cycle of the applied voltage. By referring to the curve 17 it will be clear that dimming the 15 tube by means of resistance is limited to a very narrow range because as the resistance is increased the voltage applied to the tube is decreased until finally at no time in the cycle does it attain the value indicated at 17a necessary to 20 break down the tube and initiate the discharge. That is to say, increasing the resistance in circuit with the tube decreases the instantaneous values of the voltage until finally even the maximum peak value of the voltage is less than the starting 25 voltage and consequently the discharge never starts at any time in the cycle with the result that the tube remains dark and the dimming range is limited to a very narrow range of high illumination intensities with no control at low 30 intensities.

In order to extend the dimming range of the tube means illustrated as a transformer 19 having high impedance are provided for preventing the tube voltage from attaining the break-down value 35 for a predetermined or variable portion of the alternating voltage cycle and additional means illustrated as suitable electric valve apparatus 20 are provided for rendering the impedance device 19 ineffective at desired predetermined points in the 40 tube voltage cycle. Control means 21 are provided for suitably controlling the operation of the electric valve apparatus 20.

As shown in the drawing, the primary winding of the transformer 19 is included in the connections 45 15, 16 to the supply source 11 in series relationship with the primary winding of the tube transformer 12. The transformer 19 is designed to have an exciting current that is low with respect to the exciting current required by the transformer 12 to induce the tube break-down voltage in the secondary winding thereof and is also designed to have an open circuit impedance that is large with respect to the impedance of the 50 transformer 12.

55 Although the electric valve apparatus 20 may be of any suitable type it is illustrated as a pair of electric discharge devices 22 and 23 each preferably of the three-electrode vapor electric discharge type connected for full wave rectification. 60 As shown the device 22 is provided with an anode 24, a control grid 25 and a cathode 26 whilst the device 23 is similarly provided with an anode 27, a control grid 28 and a cathode 29. The cathodes 26 and 29 are connected together as shown and 65 the anodes 24 and 27 are respectively connected to opposite terminals of the secondary winding of the transformer 19, the mid-point of which is connected to the mid-point between the cathodes 26 and 29 by means of the conductor 30. During 70 one half cycle of the alternating voltage of the secondary winding of the transformer 19, current flows from the anode 27 to the cathode 29, thence through conductor 30 and the right-hand half of the secondary winding of the transformer 19 75 whilst in the opposite half cycle current flows

from the anode 24 to the cathode 26 through conductor 30 and thence through the left-hand half of the secondary winding of the transformer 19. It will thus be seen that the electric valve apparatus rectifies both half cycles of the alternating voltage wave.

5 For the purpose of controlling the initiation of current flow in the anode circuit of the electric valve apparatus 20 during each positive half cycle of the voltages applied to the anodes 24 and 27 respectively a suitable control voltage is supplied to the grids 25 and 28 from any suitable source such for example as the source 11 to which the grids 25 and 28 are connected by means of a suitable grid transformer 31, the terminals of the secondary winding of which are respectively connected with the grids 25 and 28 and the terminals of the primary winding of which are connected to the rotor windings of the control device 21 by means of conductors 32 and 33.

10 Although the control device 21 may be of any suitable character, it is illustrated as a device for shifting the phase of the grid voltage of the electric valve apparatus 20 with respect to the anode 15 voltage. As shown, it comprises a stator winding 34 and a rotor member provided with a winding 35 in inductive relation with the stator winding. The stator winding 34 is physically similar to the polyphase winding of a polyphase dynamo 20 electric machine and its terminals are respectively connected to any suitable source such for example as the three supply lines 11, whilst the terminals of the rotor winding 35 are connected to the terminals of the primary winding of the 25 grid transformer 31.

30 The current flowing in the primary winding 34 produces a rotating magnetic field which induces a voltage in the secondary winding 35 and this voltage is applied to the grids 25 and 28 of the 35 electric valve apparatus 20. Rotation of the rotor winding 35 in space changes the phase relationship of the voltage applied to the grid with respect to the anode voltage. When the grid voltage is exactly in phase with the anode voltage 40 current begins to flow in the anode circuit as the anode voltage passes through zero and attains a positive value; whereas when the grid voltage is 180° out of phase with the anode voltage current does not flow in the anode circuit at 45 any time. For intermediate phase relationships of the grid and anode voltages, the flow of current in the anode circuit is initiated at correspondingly proportionate points in the cycle of 50 the anode voltage.

55 With the above understanding of the apparatus and its organization in the completed system, the operation will readily and easily be understood from the detailed description which follows:

60 Assuming that the rotor 35 of the control 21 occupies such a position in space that the grid voltage of the electric valve apparatus 20 is 180° out of phase with the anode voltage, flow of current in the anode circuit will not be initiated 65 at any time in the cycle of the anode voltage and consequently the transformer 19 behaves as a transformer with an open-circuited secondary winding and the reactance of its primary winding is so great that practically the entire line 70 voltage is absorbed between its terminals with the result that substantially no voltage exists across the terminals of the primary winding of the tube transformer 12. Consequently, the voltage applied to the electrode 16a and 16b 75

never attains the breakdown value 17_a and as a result the tube 10 remains dark throughout the entire cycle of the applied voltage.

Rotation of the rotor winding 35 of the phase shifting device 21 varies the phase relationship of the grid voltage of the electric valve apparatus 20 with respect to the anode voltage. Assuming that the rotor winding 35 is rotated in such a direction as to shift the phase of the grid voltage toward the inphase position with the anode voltage, current flow in the anode circuit of the electric valve apparatus is established at a point in the cycle of the anode voltage depending upon the amount of rotation of the winding 35 . At the instant that current flow is established in the anode circuit, the transformer 19 no longer acts as a transformer with an open-circuited secondary but on the other hand behaves as a transformer with a short-circuited secondary with the result that impedance is greatly diminished and there is a proportionate decrease in the voltage drop across the primary winding. This decrease in the voltage drop across the primary winding has the effect of immediately increasing the voltage drop across the terminals of the primary winding and of the secondary winding of the tube transformer 12 to such an extent that the break-down voltage 17_a is applied to the cathodes 10_a and 10_b of the tube 10 , thereby initiating the discharge which is maintained during the remainder of the half cycle of the applied voltage until the latter passes through zero.

The above described operation is of course repeated during each half cycle of the applied voltage and consequently the brilliancy of the discharge of the tube 10 as it appears to the eye is the integrated brilliancy of the tube for the portions of the voltage cycle during which there is a discharge. That is to say, if there is no discharge at any time the tube is completely dark and if the discharge is initiated at or near the beginning of the half cycle the tube appears to have maximum brilliancy whereas for a discharge initiated at intermediate points in the cycle the tube appears to have a proportionate intermediate brilliancy.

It will thus be seen that by varying the position of the rotor winding 35 relative to the stator winding 34 the instant in the half cycle of the tube voltage wave at which the discharge is initiated is controlled as desired and the intensity of illumination of the luminous discharge tube 10 likewise controlled as desired from maximum brilliancy to complete darkness without any perceptible flicker.

Although in accordance with the provision of the patent statutes, the invention is described as embodied in concrete form, the specific apparatus and connections shown are merely illustrative and the invention is not limited thereto since alterations and modifications will readily suggest themselves to persons skilled in the art without departing from the true spirit of the invention or the scope of the annexed claims.

What we claim as new and desire to secure by Letters Patent of the United States, is:

1. An illumination control system comprising a luminous discharge tube having electrodes for supporting a discharge, means for supplying an alternating voltage to said electrodes, and means for controlling the intensity of illumination of said tube comprising means external to said tube for controlling said voltage so as to vary the instant at which the discharge is initiated through-

out substantially the entire portion of each half cycle of said alternating voltage and for sustaining said discharge substantially throughout remaining portions of each half cycle.

2. An illumination control system comprising a luminous discharge tube having predetermined starting and cut off voltages, said tube having electrodes for supporting a discharge, means for applying an alternating voltage to said electrode having instantaneous values equal to or greater than said starting voltage over substantially the entire portion of each half of the voltage wave and means external to said tube for preventing the instantaneous values of applied voltage from attaining said predetermined starting voltage throughout substantially the entire portion of each half cycle of the voltage wave and thereafter applying instantaneous values of voltage greater than said cut off voltage for substantially the remainder of each half of the voltage wave.

3. An illumination control system comprising a luminous discharge tube having predetermined starting and cut off voltages, said tube having electrodes for supporting a discharge, means for applying an alternating voltage to said electrodes having instantaneous values equal to or greater than said starting voltage over substantially the entire portion of each half cycle of said alternating voltage, means for decreasing the instantaneous values of said applied voltage below said starting voltage, and means external to said tube for rendering said voltage reducing means ineffective at any selected instant during substantially the entire half cycle of said alternating voltage so that full instantaneous values of said voltage greater than said cut off value are applied to initiate and maintain the discharge through the remainder of each half cycle of the voltage.

4. An illumination control system comprising a luminous discharge tube having predetermined starting and cut off voltages, said tube having electrodes for supporting a discharge, means for applying an alternating voltage to said electrodes having instantaneous values equal to or greater than said predetermined voltage over substantially the entire portion of each half cycle of the applied voltage, means for decreasing the instantaneous values of said applied voltage below said starting voltage, control means external to said tube for rendering said voltage reducing means ineffective at a selected instant during each half cycle of the applied voltage so that instantaneous values of voltage above said cut off voltage are applied to initiate and sustain a discharge through said tube during the remainder of each half cycle, and means for controlling said control means to vary the instant at which said voltage reducing means is rendered ineffective through substantially the entire portion of each half cycle of the applied voltage.

5. An illumination control system comprising a cold cathode luminous discharge tube, means for supplying an alternating voltage to said tube, and means for gradually varying the intensity of illumination of said tube comprising electric valve apparatus for determining the instant during half cycles of said voltage for initiating the discharge of said tube and for sustaining said discharge through substantially the remaining portions of said half cycles.

6. An illumination control system comprising a luminous discharge tube having electrodes for supporting a discharge, means for supplying an alternating voltage to said electrodes, and means

- for controlling the intensity of illumination of said tube comprising a device external to said tube for controlling the voltage supplied to said electrodes to prevent discharge in said tube and 5 means for rendering said device inactive at any predetermined instant throughout substantially the entire cycle of said alternating voltage and for maintaining said device inactive throughout substantially the remaining portion of said cycle.
- 10 7. An illumination control system comprising in combination a cold cathode luminous discharge tube, means for supplying an alternating voltage to said tube, and means for controlling the intensity of illumination of said tube comprising a reactance device for preventing the discharge of said tube, and means for rendering said reactance device ineffective at any predetermined point throughout substantially the entire cycle of said alternating voltage and for maintaining said reactance device ineffective through substantially the remaining portion of said cycle.
- 15 8. An illumination control system comprising in combination, a luminous discharge tube, means for supplying an alternating voltage to said tube, and means for controlling said tube comprising a reactance device for limiting the voltage of said tube to a value below that at which a discharge is initiated, electric valve apparatus for rendering said reactance device ineffective at 20 predetermined points in the cycle of said alternating voltage, and means for controlling the operation of said valve apparatus.
- 25 9. An illumination control system comprising a luminous discharge device, means for supplying alternating voltage to said device comprising connections to a supply source including a transformer, a second transformer included in said connections having a magnetizing current materially less than that of said first mentioned 30 transformer and having a normally open-circuited secondary winding, and means for controlling said device comprising means for short-circuiting said secondary winding at predetermined points in the cycle of said alternating voltage.
- 35 40 45 10. In an illumination control system for a luminous discharge tube, means for supplying an alternating voltage to said tube comprising elec- trical connections including a transformer, a second transformer included in said connections and having an impedance sufficiently large to prevent discharge in said tube, and means for reducing the impedance of said second transformer to initiate the discharge in said tube at predetermined points in the cycle of said alternating voltage.
11. In an illumination control system for a luminous discharge tube, means for supplying an alternating voltage to said tube comprising connections to a supply source and a transformer included in said connections, a second transformer included in said connections and having an open circuit impedance of sufficient magnitude 15 to prevent the discharge of said tube, and means for controlling the intensity of illumination of said tube comprising electric valve apparatus connected to said second transformer and provided with a control grid, and phase shifting means 20 connected to said grid for controlling said electric valve apparatus to reduce the impedance of said second transformer at predetermined points in the cycle of said alternating voltage thereby to initiate the discharge in said tube.
12. In an illumination control system for a luminous discharge tube, means for supplying an alternating voltage to said tube comprising a transformer having primary power source connections and having its secondary winding connected to said tube, a second transformer having the primary winding included in said connections in series relationship with the primary winding of said tube transformer and having its secondary winding normally open-circuited, electric 30 valve apparatus provided with an anode connected to said open circuited secondary winding and also provided with a control grid supplied with alternating voltage, and means for controlling the intensity of illumination of said tube comprising means for varying the phase of said grid voltage relative to the voltage of said anode thereby to provide initiation of the discharge in said tube at predetermined points in the cycle of said alternating voltage.
